[57] CLAIM

The ornamental design for a laundry basket, as shown and described.

DESCRIPTION

FIG. 1 is a top left front perspective view of a laundry basket showing our new design;

FIG. 2 is an enlarged front elevational view thereof; the rear elevational view being a mirror image;

FIG. 3 is a top plan view thereof;

FIG. 4 is a bottom plan view thereof;

FIG. 5 is a side elevational view thereof; the opposite side being a mirror image.

FIG. 6 is a top left front perspective view of a second embodiment of the design shown in FIGS. 1-5, the only differences residing in the length of the basket and the number of elongated apertures along the front and rear walls; and,

FIG. 7 is an enlarged front elevational view thereof, the rear elevational view being a mirror image.
